US00D932038S

(12) **United States Design Patent** (10) **Patent No.:** **US D932,038 S**
(45) **Date of Patent:** **** Sep. 28, 2021**

(54) **SCALP CARE DEVICE**

(71) Applicant: **LG ELECTRONICS INC.**, Seoul (KR)

(72) Inventors: **Sunjung Park**, Seoul (KR); **Daekee Shin**, Seoul (KR); **Hophil Lee**, Seoul (KR)

(73) Assignee: **LG ELECTRONICS INC.**, Seoul (KR)

(**) Term: **15 Years**

(21) Appl. No.: **29/713,504**

(22) Filed: **Nov. 15, 2019**

(30) **Foreign Application Priority Data**

May 17, 2019 (WO) 83637

(51) LOC (13) Cl. **28-03**

(52) U.S. Cl.

USPC **D24/211**; D24/214; D24/209

(57) **CLAIM**

The ornamental design for a scalp care device, as shown and described.

DESCRIPTION

FIG. 1 is a front perspective view of the scalp care device showing our new design;

FIG. 2 is a front view thereof;

FIG. 3 is a back view thereof;

FIG. 4 is a left view thereof where the right view is a mirror image;

FIG. 5 is a top view thereof;

FIG. 6 is a bottom view thereof; and,

FIG. 7 is an exploded view showing the state that the upper cover has been detached.

The broken lines depict portions of the scalp care device that form no part of the claimed design.

1 Claim, 7 Drawing Sheets
